MECHANICAL ROSARY

Edward H. Moore, Grand Rapids, Mich.

Application June 15, 1944, Serial No. 540,532

4 Claims. (Cl. 235—123)

The invention relates to a tally device, and more especially to a rosary for religious devotional purposes.

The primary object of the invention is the provision of a device of this character, wherein it resembles a rosary, constructed to effect a tally for tabulating prayers during religious meetings or otherwise delivered, the present day rosary for religious devotional purposes being in the form of beads fastened together by a flexible element and spaced in various groups according to the system to be followed in tallying prayers, whereby considerable inconvenience is oftentimes caused by breakage, also the beads tend to readily become tangled and knotted while being carried, and furthermore, while being used in tallying prayers, if the fingers are removed, or if the rosary is dropped, the correct sequence of the prayer system becomes lost, the said device functioning to overcome or eliminate these difficulties.

Another object of the invention is the provision of a device of this character, wherein in the operation thereof, it is noiseless, and is readily and easily manipulated for accuracy in tallying purposes intended thereof, and neat and attractive in appearance.

A further object of the invention is the provision of a device of this character, which is simple in construction, thoroughly reliable and efficient in operation, strong, durable, light in weight, and inexpensive to manufacture.

With these and other objects in view, the invention consists in the features of construction, combination and arrangement of parts as will be hereinafter more fully described, illustrated in the accompanying drawings, which show the preferred embodiment of the invention, and pointed out in the claims hereunto appended.

In the accompanying drawings:

Figure 1 is a front elevation of the device constructed in accordance with the invention.

Figure 2 is a side edge view thereof.

Figure 3 is an enlarged vertical longitudinal sectional view through the device.

Figure 4 is a cross sectional view thereof.

Figure 5 is a vertical transverse sectional view taken at substantially right angles to Figure 3.

Figure 6 is a fragmentary enlarged detail sectional view showing one of the tallying buttons pushed in to counting position.

Figure 7 is a similar view showing the button moved to normal position.

Similar reference characters indicate corresponding parts throughout the several views in the drawings.

Referring to the drawings in detail, A designates generally the device constructed in accordance with the invention, and in its entirety is in the form of a cross representing a rosary for religious devotional purposes, as is the case with the ordinary present day rosary.

The device A comprises a front panel piece 10 having built at its rear a housing or casing 11, which is provided with side flanges 12 made fast or secure to the piece 10 in any suitable manner. Backing the piece 10 and properly spaced therefrom is a retention or divider plate 13, while the piece 10 has formed therein, grouped rows of spaced vertically disposed guide holes 14, these of each group being of a determined uniform size, excepting that in one group one of the holes may be in size equal to that of another group, to satisfy a common form of prayer sequence in the tallying operation of the device. The plate 13 is formed with holes 15 matching the holes 14 in the respective groups thereof.

Depressibly fitted in the holes 13 are tallying buttons 16, having outer flat heads 17, these buttons being of a corresponding size to the companion holes therefor. Each button at its innermost end is formed with a truncated cone tip 18, provided with a beveled circular crown 19, which is adapted to play in a guideway 20 interiorly of the housing or casing 11 and disposed longitudinally thereof.

Engageable about the tips 18 and confined between the piece 10 and the plate 13 are double prong inherently resilient frictional latching keys 21, each in the form of a cotter pin, so that when a selected button 16 is depressed, it will be held in this position, with the crown 19 protruded through the hole 16 companion thereto into the guideway 20, the buttons being slidably fitted in the piece 10, as will be clearly apparent.

Movably fitting the guideway 20 are release slides 22 and 23, respectively, which are aligned with the rows of buttons in a longitudinal direction of the housing or casing 11, the said slides being disposed side-by-side in edge relation to each other. The slides are provided with cam acting countersinks or depressions 24 into which enter the tips 18 of the buttons when pushed inwardly of the front panel or piece 10, so that when the selected slide 22 or 23 is moved, the buttons will be reset or moved outwardly of the panel piece 10, as is best shown in Figure 7 of the drawings, while in Figure 6 the button is shown in depressed position.

The keys 21 are anchored in proper position at the eye end 25 thereof by fasteners 26, so as to be

retained engaged with the buttons 16 at the cone tips 18 and crowns 19 thereof, these keys 21 being located in the space between the panel piece 10 and the plate 13 next thereto. These keys 21 also prevent the buttons from becoming detached or working out of the companion holes 14 in the panel piece 10.

The slides 22 and 23 are reversely projected through opposite ends of the housing or casing 11, and similarly tensioned by leaf springs 27, which are anchored thereto and to triggers 28 having tongue and groove fitting 30 with the said slides, one trigger for each slide. The slides 22 and 23 are limited in their movement for projection through the ends of the housing or casing 10 by stops 31 engaging shoulders 32, as best seen in Figure 5 of the drawings.

The tallying by the device is accomplished by depressing the selected button 16 which remains depressed until released by its slide trigger 28. The grouping of the buttons 16 as shown in Figure 1 of the drawings achieves the necessary button groupings for a common form of prayer sequence. Normally all buttons 16 are projected beyond the outer face of the panel piece 10 of the device, with the slides 22 and 23 in position for the depressing of the button selectively for tallying purposes. The cross shape formation of the device is to further the religious motif. The parts of the device A can be made from any desirable material.

What is claimed is:

1. A rosary of the kind described, comprising a front piece provided with groups of spaced holes, a housing at the back of the piece, a divider plate backing the piece, depressible buttons slidably fitting the holes and having inner truncated cone ends provided with beveled crowns, latching keys located between the piece and divider plate and frictionally engageable with the cone ends, and means movably fitting the housing and having

cam action on the crowns for resetting the buttons when depressed.

2. A rosary of the kind described, comprising a front piece provided with groups of spaced holes, a housing at the back of the piece, a divider plate backing the piece depressible buttons slidably fitting the holes and having inner truncated cone ends provided with beveled crowns, latching keys located between the piece and divider plate and frictionally engageable with the cone ends, means movably fitting the housing and having cam action on the crowns for resetting the buttons when depressed and triggers for operating the said means.

15 3. A rosary of the kind described, comprising a front piece provided with groups of spaced holes, a housing at the back of the piece, a divider plate backing the piece depressible buttons slidably fitting the holes and having inner truncated cone ends provided with beveled crowns, latching keys located between the piece and divider plate and frictionally engageable with the cone ends, means movably fitting the housing and having cam action on the crowns for resetting the buttons when depressed, triggers for operating the said means and fasteners for anchoring the keys in place.

4. A rosary of the kind described, comprising a front piece provided with groups of spaced holes, a housing at the back of the piece, a divider plate 30 backing the piece depressible buttons slidably fitting the holes and having inner truncated cone ends provided with beveled crowns, latching keys located between the piece and divider plate and frictionally engageable with the cone ends, means 35 movably fitting the housing and having cam action on the crowns for resetting the buttons when depressed, triggers for operating the said means, fasteners for anchoring the keys in place and means for tensioning the said means for moving 40 the same to a normal position.

EDWARD H. MOORE.
